INFANT'S STOMACH-BINDER AND LEGGING
COMBINATION GARMENT

Emma Borowick, New York, N. Y.

Application July 13, 1949, Serial No. 104,524

1 Claim. (Cl. 2—227)

1

The garment is an infant's stomach-binder and legging combination, and its purpose is to keep the baby warm and comfortable during cold weather.

Figure 1 of the drawing shows the front view of the garment: the binder and how it fastens, and the leggings which are attached to the binder in the front. Figure 2 depicts a rear view of the garment showing the binder unfastened and the leggings which are not attached to the binder in the back.

Figure 1

No. 1 is the band which wraps around the waist and passes through the slot: No. 3.

No. 2 is the band which wraps around the waist.

No. 3 is the slot through which the band, No. 1 passes.

No. 6 is the button for fastening the band, No. 1.

Figure 2.—The back view

No. 1 is the band which wraps around waist and passes through the slot, No. 3.

No. 2 is the band which wraps around the waist.

No. 3 is the slot through which band No. 1 passes.

No. 4 is the button hole.

No. 5 is the openings for the child's legs.

The fact that the leggings are attached to the binder, will prevent the baby from kicking them off, as he would do stockings, thus doing away with cumbersome and sometimes painful safety-pins which mothers usually use to attach the baby's stockings to the diaper with.

The fact that the leggings are not attached to the rear of the binder gives the baby ample room to kick his legs, and at the same time he is prevented from kicking the leggings off because as

2

stated in preceding paragraph the leggings are attached to the binder in the front.

The binder will be made of some type of warm, absorbent material, so that any excess urine from the diaper which is worn underneath the binder, will be absorbed by the binder and not lay on the baby's stomach.

The leggings will be made of some type of warm, nonabsorbent material to keep the child's legs warm. By saying non-absorbent material, I mean material which is not made for the specific purpose of absorbing liquid.

I claim:

15 A child's stomach-binder and legging combination having a front panel provided with a slot, arms projecting from each side of said panel, the arm on the side of the panel adjacent the slot extending partially around the wearer's waist region while the opposite arm passes through said slot to meet the first arm to fasten the garment about the wearer, and having leggings with open upper ends attached at their front upper edge to the opposite sides of the lower edge portion of said front panel, the back upper edge of said leggings being free to permit insertion of the wearer's legs, the lower regions of the leggings being adapted to prevent the exposure of the wearer's feet.
